UNITED STATES PATENT OFFICE.

ALDEN AARON STEWARD, OF RUTLAND, VERMONT.

CARBURETER.

1,067,449.

Specification of Letters Patent. Patented July 15, 1913.

Application filed July 6, 1911, Serial No. 637,122. Renewed December 18, 1912. Serial No. 737,571.

To all whom it may concern:

Be it known that I, ALDEN A. STEWARD, a citizen of the United States, residing at Rutland, county of Rutland, State of Vermont, have invented certain new and useful Improvements in Carbureters, of which the following is a specification, reference being had therein to the accompanying drawing.

This invention relates to certain new and useful improvements in carbureters and more particularly to carbureters used in connection with gas engines upon automobiles, the object being to provide means for controlling the supply of fuel when the engine is running at different speeds by increasing or decreasing the area of the atomizing chamber in order to increase or decrease the velocity of air passing the spray nozzle whereby the proper amount of liquid fuel will be sucked therefrom by the aspirating effect of the air through the passage past the spray nozzle.

Another object of the invention is to provide a novel form of valve for increasing or decreasing the size of the passage adjacent the spray nozzle which is operated simultaneously with the throttle valve whereby the engine can be run slower and more constantly without stopping or at any other intermediate speed than is possible with carbureters now in use.

A further object of the invention is to provide the valve for controlling the air into the carbureting chamber which is composed of oppositely disposed members adapted to be forced toward each other simultaneously whereby the size of the passage will be decreased at the center thereof adjacent the spray nozzle in order to allow the velocity of air to be increased in order to suck the required amount of hydrocarbon fuel into the carbureting chamber to produce a highly combustible mixture.

A still further object of the invention is to provide a carbureter which is exceedingly simple and cheap in construction and one in which the operating means for the valves are so mounted that a very durable carbureter is formed.

Other and further objects and advantages of the invention will be hereinafter set forth and the novel features thereof defined by the appended claims.

In the drawings—Figure 1 is a side elevation of a carbureter detached; Fig. 2 is a similar view with the side of the casing re-

moved in order to show the construction of the interior; Fig. 3 is a vertical section; Fig. 4 is a view similar to that of Fig. 3 showing the valve partly closed in order to decrease the area for increasing the velocity of air being sucked into the engine; and Fig. 5 is a detail view of the modified form of spray nozzle.

Like numerals of reference refer to like parts in the several figures of the drawings.

In the drawings, 1 indicates an engine cylinder which is provided with the usual inlet pipe 2 to which is connected a casing 3 forming the carbureting chamber of the carbureter which is provided with an open end into which extends a feed pipe 4 having a centrally arranged spray nozzle 5 and as herein shown, said nozzle is pointed for a purpose later described. The feed pipe 4 is connected to a reservoir 6 adapted to contain liquid hydrocarbon which is of the ordinary construction of reservoir now in use and is provided with a needle valve 7 for controlling the flow of oil through the feed pipe and is provided with a supply nipple 8 controlled by a valve 9, said nipple being adapted to be connected to the pipe from any suitable source of supply.

The upper end of the casing 3 is contracted as shown at 10 in which is mounted a throttle valve 11 carried by a valve stem, 12 having an operating lever 13 mounted thereon to which is adapted to be connected the usual form of operating means, not shown. Fixed on the valve stem 12 are diverging arms 14 carrying a cam 15 which is secured in its adjusted position thereon by screws 16, said cam being adapted to engage a stud pin 17 working through a slot formed in the face of the casing, said slot being closed by a washer 18 mounted upon the stud pin and held tightly against the face plate of the casing in order to form a tight joint by a spring 19 and, as herein shown, is substantially U-shaped in order to form a guide for the stud pin as the same is moved.

My improved valve for accomplishing the desired result comprises a pair of flat springs 20 and 21, the lower ends of which are secured to the respective walls of the casing by blocks 22 and the upper ends are secured to the side bars 23 of a frame 24 which is slidably mounted therein and on which the stud pin 17 is mounted. It will be seen that as the frame is forced down-

wardly by the cam, the springs will be bowed toward each other in order to decrease the area of the carbureting chamber which will increase the velocity of the air passing into the open end of the casing, thereby regulating the amount of oil being sucked out of the spray nozzle by the aspirating effect. In the form herein shown, the casing is rectangular in shape but it is, of course, understood that the same can be made in any shape desired and the spring members constructed to conform to the shape. By this construction, the springs are forced inwardly in such a manner that the intake of air to each side of the nozzle and the passage of the atomized hydrocarbon will have a clear passage which is unobstructed by any lateral projection, the springs bowing on curved lines to allow the contraction of the size of opening to be formed in such a manner that a great advantage is obtained over previously constructed valves. It will be seen that by forming the spray nozzle pointed, the springs can be forced toward each other to such an extent that the opening can be practically closed, thereby increasing the velocity of the air to such an extent that the desired amount of liquid hydrocarbon will be drawn out of the spray nozzle and atomized to obtain the best possible mixture. By mounting the valve in this manner and operating the same by a cam from the valve stem of the throttle valve, the area will be increased or decreased as the throttle valve is opened or closed in order to give the correct velocity of air for the opening of the throttle or such velocity of air for the opening of the throttle that it will give the best mixture and as shown in Fig. 5, the valve is practically closed when the throttle valve is in the same position.

While I have shown and described a particular form of throttle valve, it is, of course, understood that any form of throttle valve can be employed and that other means than that herein shown and described for operating the valve for increasing or decreasing the velocity of air whereby the air inlet passage way into and through the carbureting chamber will be controlled by the throttle valve. I have also found that, under certain conditions, better results can be obtained by providing a multiple jet spray nozzle 28 as shown in Fig. 5 which will allow the jets to be reduced in size to such an extent that the air inlet passage way can be decreased in area to a greater extent than with a single jet nozzle, thereby increasing the velocity of the air past the spray nozzle in order to allow the same to draw the desired amount of hydrocarbon therefrom to produce the desired mixture of a high type.

From the foregoing description, it will

be seen that I have provided means for producing a high velocity of air past the spray nozzle at all times and under all conditions which will draw the desired amount of fuel and thoroughly spray the same in order to allow the engine to be run at any speed desired without wasting any fuel and at the same time the operator has perfect control of the engine whereby the same may be thrown from a high to a low speed by simply operating the throttle valve which simultaneously controls the air inlet passage way.

From the foregoing description, it is thought that the operation of the carburetor can be clearly understood, but in order to allow those not skilled in the art to readily appreciate the advantages obtained, the following description of the operation of the same is given: As air is sucked into the casing through the air inlet passage way by the engine, liquid hydrocarbon is drawn out of the spray nozzle and atomized in the carbureting chamber from which it is drawn into the cylinder of the engine in the ordinary manner. Heretofore, great difficulties have been encountered with carburetors when the speed of the engine was reduced as no means was provided for reducing the supply of air, thereby making it impossible to maintain at all times a proper proportion of liquid hydrocarbon and air. By providing the valve for reducing the area in order to increase the velocity of air at the point of the spray nozzle, these difficulties are overcome and a carburetor is formed which will allow the engine to be run slower and more constantly without stopping.

Having described my invention and set forth its merits what I claim and desire to secure by Letters Patent is—

1. In a carburetor, the combination with a casing having a carbureting chamber and an air inlet passage, a feed pipe extending through the air inlet passage into the chamber and provided with a spray nozzle, a valve for controlling the passage of air through said passage, said valve comprising a pair of oppositely disposed flat members of substantially the same width as said passage adapted to be flexed toward each other adjacent the spray nozzle.

2. A carburetor having a carbureting chamber provided with an air inlet passage, a spray nozzle, a valve for controlling said air passage, said valve comprising oppositely disposed spring members having fixed and slidably mounted ends, and means for reciprocating said slidably mounted ends for flexing said spring members toward the spray nozzle.

3. A carburetor having a carbureting chamber provided with an air passage, a spray nozzle, flat spring members mounted in said passage having fixed and slidably

- mounted ends and means for flexing said spring members against said spray nozzle in order to decrease the area of the air passage by reciprocating said slidably mounted ends.
- 5 4. In a carbureter, the combination with a casing having a carbureting chamber provided with an air inlet passage and an outlet passage, a feed pipe having a spray nozzle extending into said air inlet passage, 70 10 spring members for contracting the air passage, means for flexing said spring members, a throttle valve, and means carried by the throttle valve for actuating the flexing means.
- 15 5. A carbureter having a carbureting chamber provided with an air inlet passage, a spray nozzle arranged centrally within said air inlet passage, spring members arranged within said air inlet passage, means 75 20 for flexing said spring members toward the spray nozzle, and means for controlling the outlet passage of said carbureting chamber.
6. A carbureter having a carbureting chamber provided with an air inlet passage, 80 25 springs secured at one end to the walls of said passage, a frame slidably mounted in said passage to which the other ends of said springs are connected, a pin carried by said frame, and means engaging said pin for 85 30 flexing said springs.
7. In a carbureter, the combination with a casing forming a carbureting chamber having an air inlet passage and an outlet passage, a throttle valve for controlling the 90 35 outlet passage, a spray nozzle arranged within the air inlet passage, springs having their upper ends connected to said casing within said passage, a frame to which the lower ends of said springs are connected, a 95 40 pin carried by said frame extending through said casing, and a cam carried by the throttle valve engaging said pin for simultaneously flexing said springs toward the spray nozzle when the throttle valve is 100 45 partly closed.
8. A carbureter comprising a casing having a contracted outlet at its upper end and an air inlet passage at its lower end forming a central carbureting chamber, a 105 50 throttle valve mounted in said contracted outlet passage having a valve stem extending outwardly therefrom, a feed pipe extending into said air inlet passage having a pointed spray nozzle at its end, springs 110 55 arranged within said air inlet passage having fixed and movable ends, and means carried by the throttle valve stem for actuating said springs to flex the springs against the spray nozzle.
- 60 9. A carbureter comprising a casing having a carbureting chamber provided with an air inlet passage and an outlet passage, a throttle valve for controlling the outlet passage, oppositely disposed spring members 115 65 for controlling the inlet passage, means for flexing said spring members toward the center of said passage, said means being actuated by the throttle valve.
10. In a carbureter, the combination with a casing having a carbureting chamber provided with an air inlet passage and an outlet passage, a throttle valve for controlling the outlet passage having a stem extending outwardly from said casing, arms carried by said valve stem, a cam carried by said arms, springs arranged within said air inlet passage having fixed and movable ends, and a member carried by the movable ends of said springs adapted to be engaged by 120 70 said cam for flexing said springs.
11. A carbureter comprising a casing having a carbureting chamber provided with an air inlet passage and an outlet passage, 80 75 said casing being provided with a slot, a movable frame mounted in the air inlet passage having a pin extending through said slot, springs fixed to said movable frame having their opposite ends fixed to said casing, a throttle valve, and a cam carried by the throttle valve engaging said pin. 85 90
12. A carbureter comprising a casing having a carbureting chamber provided with an air inlet passage and an outlet passage, a throttle valve for controlling the outlet passage, a cam carried by said throttle valve, a movable frame mounted within said air inlet passage, springs having their lower ends fixed to said frame and their upper ends secured to said casing, a spray nozzle arranged between said springs, a pin carried by said frame working through a slot formed in said casing, a washer arranged on said pin over said slot, a spring for holding said washer against said casing, said spring forming a guide for said pin, said pin being adapted to be engaged by said cam so as to expand said springs. 95 100 105
13. A carbureter having a carbureting chamber provided with an air inlet passage, a valve for closing said air inlet passage 110 110 formed of oppositely disposed springs having fixed and movable ends, means for flexing said springs, said means being actuated simultaneously with the closing of the throttle valve.
14. A carbureter having a carbureting chamber provided with an air inlet passage and an outlet passage, one wall of said carbureting chamber being provided with a slot, a frame slidably mounted in said casing 120 125 having a pin extending through said slot, a washer arranged on said pin over said slot, a U-shaped spring bearing against said washer and forming a guide for said pin, spring members carried by said frame having fixed ends, and a throttle valve for closing the outlet passage of said casing, said throttle valve having a cam engaging said pin.
15. A carbureter having a carbureting 130

chamber provided with an air inlet passage and an outlet passage, a frame slidably mounted in said carbureter having an outwardly projecting pin, spring members carried by said frame having fixed ends, a throttle valve for closing the outlet passage, diverging arms carried by said throttle valve, a cam adjustably mounted on said arms co-acting with said pin, and a spray

nozzle arranged within the carbureter between said spring members.

In testimony whereof I affix my signature in presence of two witnesses.
